TOILET APPLIANCE

Chester G. Myers, St. Petersburg, Fla., and William Ilgenfritz, York, Pa., assignors to Leschey Myers Manufacturing Co., Hanover, Pa., a corporation of Delaware

Application November 25, 1938, Serial No. 242,204

2 Claims. (Cl. 4—239)

This invention relates to toilet seats for infants, and particularly to toilet seats of the type adapted for attachment to bowls provided with adult seats.

5 An object of the invention is to provide an improved auxiliary seat for children which is capable of being readily applied to and removed from any conventional toilet.

Another object of the invention is to provide 10 an improved auxiliary toilet seat which may be raised and lowered independently of the main seat.

Another object of the invention is to provide 15 an improved supplementary toilet seat having means by which the same may be readily attached to and removed from the pivot bolt of any conventional toilet without marring the finish on a toilet.

Another object of the invention is to provide 20 an improved supplementary toilet seat having a pair of parallel arms extending therefrom, the extremities of said arms being formed with a plurality of oppositely disposed spring fingers adapted to engage the pivot bolt of a conventional toilet and thereby pivotally connect the 25 supplementary seat to the toilet.

With the foregoing and other objects and advantages in view, the invention consists in the preferred construction and arrangement of 30 the several parts which will be hereinafter fully described and claimed.

In the accompanying drawings:

Figure 1 is a plan of a conventional toilet showing the supplementary toilet seat attachment applied thereto;

Fig. 2 is an enlarged vertical longitudinal section taken on the line 2—2 of Fig. 1;

Fig. 3 is a perspective of the supplementary toilet seat attachment;

40 Fig. 4 is a bottom plan of a modified form of arm for the supplementary seat;

Fig. 5 is a side elevation of the arm shown in Fig. 4;

Fig. 6 is a bottom plan of the inner end portion of another form of arm for the supplementary seat;

Fig. 7 is a side elevation of the arm shown in Fig. 6;

Fig. 8 is a bottom plan of the inner end portion 50 of another form of arm for the supplemental seat;

Fig. 9 is a side elevation of the arm shown in Fig. 8;

55 Fig. 10 is a plan of another form of arm for the supplemental seat; and

Fig. 11 is a vertical longitudinal section taken on the line 11—11 of Fig. 10.

Referring to the drawings, the conventional toilet may comprise a bowl 11 having a rear extension 12 to which are affixed standards 13, each 5 having an eye 14 for a pivot bolt 15.

A conventional seat 16 and a lid 17 are mounted for rotatable movement about the longitudinal axis of the bolt 15. The seat 16 is rotatably secured to the pivot 15 by brackets 18, and the 10 lid 17 is similarly secured by brackets 19. The seat 16 is formed with the usual substantially elliptical opening 20.

Adapted to be attached to the conventional seat structure is a supplementary seat 21 intended primarily for the use of children and infants.

The seat 21 may be formed of any desired configuration but preferably of a thickness to fit between the seat 16 and the lid 17 when the lid is 20 disposed in lowered position, as shown by broken lines in Fig. 2.

An opening 22 is formed in the supplementary seat 21, said opening 22 being somewhat smaller in area than is the area of the opening 20. 25

For the purpose of providing means by which the supplementary seat 21 may be easily applied to and removed from the seat 16, the rear portion of the seat 21 has fixed thereto a pair of arms 23.

In order that the supplementary seat structure 30 21 will be of light weight the main body portion of said seat may be formed of plywood, and when said seat is formed of such material the arms 23 may be secured thereto by means of rivets 24, as illustrated in Figs. 1, 2 and 3, or the arms 35 23 may be secured to the seat 21 by other means, as will be hereinafter more fully described.

Preferably the arms 23 are formed of flat sheet metal strips having suitable resilient characteristics. The outer extremity of each arm is split 40 or cut lengthwise of the arm, as indicated at 25 and 26 (Fig. 3) so as to form three fingers 27, 28 and 29, which fingers constitute means for clamping the seat 21 on to the pivot bolt 15.

The finger 28 is disposed between the fingers 45 27 and 29. The finger 28 is bent downwardly to form an arcuate or substantially semi-circular portion terminating in a reversely curved flanged end or tip 30. The fingers 27 and 29 are both bent upwardly to form similar arcuate or substantially 50 semi-circular portions terminating in reversely curved flanged ends or tips 31 and 32, respectively. The arcuate portions of the fingers 27, 28 and 29 are adapted to be held under their inherent resiliency to afford ready attachment to the pivot 55

bolt 15. The tips 30, 31 and 32 of the fingers are spaced apart so as to afford unobstructed surfaces to facilitate attachment of the supplementary seat 21 on to the pivot bolt 15. By constructing the arms 23 with the fingers 27, 28 and 29 the supplementary seat 21 as well as the main seat 16 and the lid 17 are adapted to be rotated longitudinally about the axis of the bolt 15.

It will be noted that the hinge provided by the fingers 27, 28 and 29 permits the supplementary seat 21 to be raised to an upright position and be positioned against the lid 17 when the lid is disposed in upright position, as shown in Fig. 1, and the center of gravity will so fall that the seat 15 21 will have no tendency to swing back.

The seat 21 will under normal conditions remain in an upright position adjacent to the lid 17 due to the frictional engagement of the fingers 27, 28 and 29 with the pivot bolt 15.

20 Due to the fact that the arms 23 are formed of resilient strips of metal the supplementary seat 21 is adapted to be applied to a toilet either in the manner illustrated in Figs. 1 and 2 or in a reversed or upside down position. This is due 25 to the lightness of the material used in constructing the arms 23, so that when weight is applied to the seat 21, the seat will conform to the contour of the main toilet seat 16 on which it rests.

In the form of the invention shown in Figs. 4 30 and 5, the arm 23 is formed with a heart-shaped head or inner end portion 35. Triangular shaped prongs 36 are formed at suitable intervals around the periphery of the end 35, said prongs being bent at right angles to the plane of the main 35 surface of the arm and being adapted to be driven into the seat 21 (indicated by broken lines, Fig. 5) so as to firmly secure the arm to said seat.

The prongs 36 are, as shown in Fig. 4, disposed at the widest portion of the end 35. This is desirable with some kinds of material used in constructing the seat 21, since by spacing the prongs far apart the arm will be more firmly secured to said seat.

However, in some instances it may be desirable 45 to form the arm 23 with a head or inner end portion 37 having triangular-shaped prongs 38 and 39 disposed in the manner shown in Figs. 6 and 7. In this form of the invention the prongs 39 are disposed adjacent to the junction of the head 50 37 with the main body of the arm.

In the form of the invention shown in Figs. 8 and 9, the arm 23 is formed with an enlarged inner end or head 41 having a plurality of prongs 42 depending from the interior of the head, said 55 prongs being formed by constructing V-shaped slits in the material and bending the slotted material or tongue downwardly.

In the form of the invention shown in Figs. 10 and 11, the arm 23 is formed with an enlarged

inner end or head 44. At a point adjacent to the junction of the head 44 with the main body portion of the arm, a transverse groove or notch 45 is formed in the arm. The construction is such that the underside of the portion of the 5 arm at which the notch or groove 45 is formed there is a depending bead 46. In order to secure the arm having the bead 46 to the supplementary seat, a staple 47 is employed. When the staple is fastened into the seat material the bead 46 10 will be forced into the material so that the arm will be interlocked with the seat.

Having thus described our invention, what we claim is:

1. The combination with a main seat assembly 15 permanently associated with a toilet bowl and including a horizontally disposed bolt for pivotally connecting the rear portion of the main seat to the bowl, of an auxiliary seat adapted to overlie the main seat and having an arm secured thereto 20 and extending rearwardly therefrom, said arm being formed of a single piece of resilient sheet metal having each end portion thereof enlarged in width with respect to the main body portion thereof, means engageable with the enlarged inner 25 end portion of said arm and adapted to be embedded in the body of the auxiliary seat for fastening the arm to said auxiliary seat, a pair of slits formed lengthwise in the enlarged outer portion of said arm so as to form three fingers, 30 all of said fingers being curved lengthwise thereof, the intermediate finger being curved in a direction opposite to the direction in which the two end fingers are curved so that all of said 35 fingers extend partly around the bolt to thereby provide means for readily detachably securing the auxiliary seat to the toilet.

2. A toilet appliance comprising an auxiliary seat adapted to overlie a main seat permanently associated with a toilet bowl and including a horizontally disposed bolt for pivotally connecting the rear portion of the main seat to the bowl, an arm secured to the auxiliary seat and extending rearwardly therefrom, said arm being formed of a single piece of resilient sheet metal having each end portion thereof enlarged in width with respect to the main body portion thereof, means 45 formed integrally around the periphery of the enlarged inner end portion of said arm and adapted to be embedded in the body of the auxiliary seat 50 for securing the arm to said auxiliary seat, and a plurality of alternately arranged upwardly and downwardly curved spring fingers formed in the enlarged outer end portion of said arm, said fingers being adapted to partly surround said 55 bolt so as to pivotally connect the auxiliary seat to the toilet.
